KAREL VESELY AND KAREL LUSTIG, OF PRAGUE, CZECHOSLOVAKIA.

AUTOMATIC REGULATION OF ARC LAMPS.

Application filed March 27, 1926, Serial No. 98,043, and in Czechoslovakia January 6, 1925.

This invention relates to automatic regulation of arc lamps and has among its objects the provision of improved means and method for automatically maintaining the light source, which is located in the crater formed in the end of the positive electrode of the lamp, in a pre-determined position with respect to the co-operating parts of the lamp.

10 The devices used heretofore for the regulation of the position of the lamp carbons, in particular the location of the crater, have been designed either on the optical or thermal principle. The light emanating from the positive electrode was concentrated by a lens upon a suitable thermometer, which in turn controlled the circuit for moving the positive carbon. Other regulating devices used selenium for controlling the movement of the carbon.

15 The foregoing regulating arrangements are oversensitive or have too much inertia, or hysteresis, resulting in either too quick or too slow regulation, and have proved unsatisfactory.

According to the present invention the movement of the positive carbon and the location of the light source associated with the crater thereof, is regulated by means of an auxiliary electrode which is held in a predetermined point in space, and so arranged that the voltage between said electrode and the arc electrode that is to be regulated, is applied to so control the movement of said arc electrode as to maintain the crater portion at the end thereof at a predetermined point in space, as defined by the location of the auxiliary electrode. The particular feature of the invention is the arrangement whereby the auxiliary electrode, which is usually being consumed by the arc adjacent thereto, is so automatically fed that its end is always located in the same regulating position in the space so that the crater will always be located in the desired position with respect to the parts of the arc lamp with which it is to cooperate.

20 The foregoing and other objects of the invention will best be understood from the accompanying drawings in which

Fig. 1 is a diagrammatic view of an arc-lamp regulating system to which our invention may be applied.

25 Fig. 2 is a view similar to Fig. 1 showing a modification of said regulating system;

Fig. 3 is a diagrammatic, plan view of an arc regulating system embodying our invention; and,

Fig. 4 is a side view of a part of the mechanism shown in Fig. 3.

Referring to Fig. 1, an arc lamp has a positive electrode 1 and a negative electrode 2 fed by means of suitable feeding mechanisms 3 and 4 to maintain an arc therebetween.

As pointed out above, it is important that the portion of the arc which constitutes the source of the light, that is, the crater 5 in the positive electrode, shall be stationary in space, that is, shall be definitely located with respect to certain stationary parts of the lamp with which it is to co-operate. It is an object of the present invention to provide means whereby the mechanism 3 which feeds the positive electrode 1 as it burns off in the arc, shall be so regulated that said light source, or crater, shall continuously remain in the same position in space, irrespective of the consumption of the electrode in the arc.

To this end we place near the point where the crater 6 is to be located, an auxiliary electrode 7 and energize with the voltage drop between said electrode and the anode 1, a regulating device 10 which is shown as comprising a relay 11, connected between the auxiliary electrode 7 and the anode 1. The energization of the relay 11 controls the closure of contact members 12 in a circuit 13 which serves to energize and operate the anode feeding mechanism 3.

As is well known, the major portion of the arc voltage is concentrated near the crater 5, and accordingly, when the carbon 1 burns off and the crater recedes back from the space where it is intended to be mounted, a relatively high voltage will be applied through the auxiliary electrode 7 to the relay 11, closing the contacts 12 in the circuit 13, which energizes the anode feeding mechanism 3, thus causing the anode to be advanced toward the position where the crater is intended to be held. As soon as the positive carbon 1 is driven so far toward negative electrode 2 that it touches the end of the auxiliary electrode 7, there will be substantially no voltage applied to the relay coil 11, the contacts 12 in the energizing circuit of the feeding mechanism 3 will be opened and the node feeding will be stopped.

As soon as the anode terminal has burned off again, the feeding cycle will repeat itself as before.

The regulating action of the anode movement described above depends on the correct positioning of the end of the auxiliary electrode 7, and the entire regulation process would become ineffective if the auxiliary electrode would slowly be consumed by the arc near which it is disposed. Our invention is particularly concerned with means for offsetting the consumption of said auxiliary electrode, and thus securing effective control of the location of the anode crater.

As shown in Fig. 2, we may provide to this end, in addition to the mechanism for feeding the anode 1, a mechanism 21 for feeding the auxiliary electrode 7, and regulate said mechanism by means of a regulating device 22 similar to that employed for regulating the anode feeding device. The regulating mechanism 22 comprises a relay 23 which is connected between the auxiliary electrode 7 and the anode 1. The relay opens and closes a pair of contacts 24 which controls the energization of the auxiliary-electrode feeding mechanism 21.

The relay 23 is so adjusted that in case the auxiliary electrode 7 is in contact with the positive carbon 1, or with the arc, the contacts 24 are opened and the feeding mechanism 21 of the auxiliary electrode is de-energized. As soon as the auxiliary electrode 7 is consumed by the arc to such an extent that it ceases to be in direct contact with either the positive carbon or the arc, the relay 23 closes the contacts 24, thereby energizing the feeding mechanism 21 and advancing the auxiliary-electrode 7 until contact with the arc or the carbon is again established.

It is thus possible to compensate the effect of the burning off of the auxiliary electrode and obtain close regulation of the position of the crater just as if the auxiliary electrode were of a material that is not consumed by the arc.

In the preferred embodiment of our invention shown in Figs. 3 and 4, we have shown an arrangement which compensates for the consumption of the auxiliary electrode on which the regulation of the anode movement depends, with a still higher accuracy than the arrangement shown in Fig. 2. In addition, the preferred arrangement has special provisions for reducing the amount of consumption of the auxiliary electrode to a minimum, while at the same time obtaining the full regulating effect that can be secured therefrom. In the improved arrangement of Fig. 3, the tip of the auxiliary electrode 7 is not held continuously near the crater and the arc, but is given a swinging cyclical movement indicated by the dotted

curve 31, 32, 33, that is, the auxiliary electrode 7 is withdrawn from the point 31, which corresponds to the point at which it is to exercise the regulating action on the anode feeding mechanism, and swung backwardly to the point 32 of the dotted curve, and then advanced to the point 33 until it contacts with the side of the positive carbon 1 back of the arc. The auxiliary electrode 7 is then moved back to the point 31 and remains there for a short period during which it is connected to control the anode feeding mechanism, and then the cyclical movement along the curve 31, 32, 33, repeats itself in continuous succession. While this cyclical swinging movement of the arc tip of the auxiliary electrode 7 takes place, the electrode is being fed forwardly to the arc and since it is being brought in contact with the carbon 1 at 33 during each cycle, this contact thus determines the position of the upper end of the electrode when it is held at 31 near the arc to exercise the regulating action.

In other words, instead of controlling the movement of the auxiliary electrode 7 toward the arc, for compensating the consumption of said electrode by the arc, in response to the variation of the voltage drop between the auxiliary electrode and the anode, as in Fig. 2, the arrangement in Fig. 3 cyclically withdraws the auxiliary electrode from the arc and brings the end of said electrode which is to exercise the regulating action into abutment against a point which is fixed in space, and thereby determines the position of the end of said auxiliary electrode when it is, at a subsequent moment of the cycle, brought back into the arc for regulating the anode movement.

The special arrangement shown in Fig. 3 for carrying out the above described regulation of the electrode movement comprises a rocking lever 35 arranged to be swung around a pivot 36 at one end thereof. The other end 37 of the rocking lever is connected through a rod 38 to an eccentric 39 which is driven by a pinion 40 engaging a gear wheel 41 that is rotated by a suitable motor not shown in the drawing. The gear 41 is directly connected to a second eccentric 41 which serves to impart through a pin and slot connection 43, a swinging movement to an electrode guide 44 that has at its upper end a pivotal connection 45 with the rocking lever 35.

Longitudinally along the electrode guide 44 is mounted a bushing 46 in which is slidably mounted the auxiliary electrode 7. The auxiliary electrode is frictionally held in the bushing 46. The gear wheel 41 has also a worm drive connection 47 with a threaded rod 48 which serves to propel upwardly an electrode feed member 49 which is arranged

to push the auxiliary electrode 7 towards the arc.

Since the gear wheel 41 has twice as many teeth as the pinion 40, the end of the electrode 7 will drive the swinging movement along curve 31, 32, 33 referred to above. On the other hand, the pitch of the thread on the rod 48 is so chosen that the upward movement of the electrode propelling member 49 tends to move said electrode faster than the rate at which its end is being consumed by the arc. If the vertical position of the auxiliary electrode 7 were fixed, the end of the electrode would, after a certain period, pass the point 31 which may be regarded as a regulating point. The position of the rod is, however, not fixed. The auxiliary electrode swings and at a certain point of the swinging cycle its end strikes the carbon 1, thus fixing the end of said carbon, and when the auxiliary rod moves back to the vertical position, its end is exactly at the regulating point 33, irrespective of the amount of the burning thereof in the arc. The contact with the arc is, therefore positive.

With the foregoing arrangement the auxiliary electrode maintains positive contact with the arc, since upon hitting the anode 1 at 33, it moves down in the bushing 45 to such a position that when swinging back along 33, 32 to 31, the end comes exactly to the point 31 at which the regulating action is to be exercised.

The circuit which energizes the feeding mechanism of the anode is closed through the contact members 53 which are operated by a relay 54, that is connected between the anode 1 and the auxiliary electrode 7, as in the arrangement shown in Fig. 1. The circuit which energizes the feeding mechanism of the anode has included therein an additional pair of contact members 55 and 56, which are closed, circuited by a contact segment 57 operated by the gear wheel 41 to close the circuit only when the auxiliary electrode 7 has its tip at the point 31 during which it is adapted to exercise the regulating action. Through this arrangement, the movement of the positive carbon can take place only during the instant when the end of the auxiliary electrode 7 is near the regulating point 31 of the arc. This provision prevents the operation of the control equipment during any other period of the swinging motion of the auxiliary electrode by reason of an instantaneous irregularity of the arc.

In order to prevent danger to the lamp mechanism in case the propelling member 49 reaches its highest upper position, indicated at 60 by dotted lines, that is, at a time when the auxiliary rod has been burned down to the shortest admissible length, the lamp is arranged to be automatically cut

out of service by a switch 61 operated by said propelling member 49.

We claim as our invention:

1. In an arc lamp, a pair of electrodes adapted to produce an arc, means for feeding one of said electrodes, an auxiliary electrode adjacent to the arc tip of said last mentioned electrode, means controlled by the current passing through said auxiliary electrode for controlling said feeding means, and means responsive to the operation of said arc for automatically compensating for the burning of said auxiliary electrode.

2. In an arc lamp, a main electrode and an additional electrode co-operating with said main electrode for producing an arc, said main electrode having a tip required to be located at a predetermined fixed position with respect to the stationary parts of said lamp irrespective of the burning of said tip by the arc, means for feeding said main electrode, electro-magnetic means for bringing into operation said feeding means, and an auxiliary electrode adjacent to the tip of said main electrode and in circuit with said electro-magnetic means, said auxiliary electrode being adapted to engage the arc to close a circuit through said electro-magnetic means, and means responsive to the operation of said arc for automatically feeding said auxiliary electrode to offset the consumption thereof by said arc.

3. In an arc lamp, a main electrode and an additional electrode adapted to co-operate with said main electrode to maintain an arc, means for feeding said main electrode toward the arc to compensate for the consumption thereof and maintain the tip of said main electrode at a predetermined point with respect to the stationary parts of the lamp, an auxiliary regulating electrode having its tip engaging said arc, a regulating mechanism connected between said main electrode and said auxiliary electrode to regulate the feeding of said main electrode for maintaining the tip of the latter at the aforesaid position, and means for periodically withdrawing said auxiliary electrode from the arc and adjusting the location thereof so that the tip of said auxiliary electrode is at a pre-fixed point in space with respect to the stationary parts of said lamp when carrying out the regulation of the movement of the main electrode.

4. In an arc device, a main electrode, an auxiliary electrode arranged to maintain an arc with said main electrode, a mechanism for feeding said main electrode into the arc to compensate for the consumption thereof, an auxiliary electrode having a tip adapted to engage said arc near the tip of said main electrode, regulating means connected between said main electrode and said auxiliary electrode to so control said mechanism in response to the voltage between said auxil-

iary electrode and said main electrode as to maintain the tip of said main electrode at a fixed position with relation to the stationary parts of said light, and means for periodically withdrawing said auxiliary electrode from said arc.

5. An arrangement as defined by claim 4, characterized by means for fixing the position of the auxiliary electrode while removed from the arc so that the tip thereof when in engagement with the arc is at a predetermined fixed position in space with respect to the stationary parts of said device.

6. An arrangement as defined by claim 4, characterized by means for causing the end of said auxiliary electrode to abut against a substantially fixed point of said device to thereby pre-fix the location of the tip of said auxiliary electrode when in regulating engagement with said arc.

7. In an arc device, a main electrode, an auxiliary electrode arranged to maintain an arc with said main electrode, a mechanism for feeding said electrode into the arc, an auxiliary electrode having a tip adapted to engage said arc near the tip of said main electrode, regulating means connected be-

tween said main electrode and said auxiliary electrode for so controlling said mechanism as to maintain the tip of said main electrode in a predetermined position with respect to the tip of said auxiliary electrode when in engagement with the arc, means for feeding said auxiliary electrode into the arc to offset the consumption thereof, and means for locating the tip of said auxiliary electrode in carrying out said regulating action, said means comprising means for withdrawing the tip of said auxiliary electrode from the arc, means for causing said auxiliary electrode to abut against a point that is substantially fixed with respect to said device, and means for returning said tip into the arc to carry out said regulating action.

8. An arrangement as defined by claim 7, characterized by means for restricting the feeding movement of the main electrode to a period during which said auxiliary electrode is in a predetermined position in space.

In testimony whereof, we have hereunto subscribed our names this 1st day of February, 1926.
